Attorney.

UNITED STATES PATENT OFFICE

LOUIS P. REIMANN, OF BUFFALO, NEW YORK

ROOF BRACKET OR JACK

Application filed November 26, 1930. Serial No. 498,329.

My invention relates to improvements in a roof scaffold bracket or jack; and it has for one of its objects the provision of a bracket or jack adapted particularly for use when shingling or otherwise covering roofs, or when repairing old roofs.

Another object of my invention is the provision of a bracket or jack of the kind mentioned, which is durable, simple in construction, adjustable to roofs of various pitches or inclinations, and one which can be easily applied and as readily removed without damaging any portion of a new roof already completed, or any serviceable shingle or other covering units of an old roof, when making repairs to such roof.

With the above and other objects in view to appear hereinafter, the invention consists in certain novel features of construction, and in the combination and arrangement of parts to be hereinafter described and more particularly pointed out in the subjoined claims.

In the drawing:

Fig. 1 is a perspective view of the upper portion of a building in the course of construction, showing the same partly covered with shingles and the manner of attaching my improved bracket or jack thereto, with a view of cooperation with a similar bracket or jack spaced at a distant point along the roof, so as to enable a suitable plank or support to be placed upon both brackets or jacks with a view of serving as a walk to carry the weight of workmen applying shingles or other covering units to the roof, or repairing such on an old structure.

Fig. 2 is a vertical section through a roof, and through my improved bracket or jack, showing the manner in which it is supported by several courses of shingles on a roof, and the manner in which one or more courses cover the upper end of the bracket or jack, yet allow the latter to be easily detached from underneath such covering courses.

Fig. 3 is a plan view of the device applied to a roof while folded or collapsed.

Fig. 4 is a longitudinal section through the device taken on line 4—4, Fig. 3.

Fig. 5 is an enlarged transverse section

taken on line 5—5, Fig. 4, looking in the direction of the arrow crossing said line.

Fig. 6 is a detached perspective view of the comparatively thin supporting member.

Fig. 7 is a detached perspective view of 55 the brace member.

Fig. 8 is a detached perspective view of the lift or jack member.

Reference being had to the drawing in detail, the numeral 9 designates the roof boards 60 of a roof forming the foundation for the shingles 10, or other covering units of the roof.

Covering units of various kinds are commonly employed on roofs; some being of wood, others of slate, and still others of asbestos and other compositions, and these are invariably laid in horizontal rows on the foundation of the roof in overlapping arrangement.

In the drawing I have shown the usual 70 elongated wooden shingles which are laid in horizontal rows or courses, and my improved bracket or jack is adapted to be applied to the uppermost layer or course of shingles conveniently reached by the workmen from 75 a lower position during the operation of applying the shingles or other covering to the roof. For this purpose a plurality of nails 11 are driven into a shingle of the uppermost course laid so that the headed ends of the 80 nails extend a trifle above the outer surface of the shingle, and my improved bracket or jack is hung on said nails in the manner to presently appear. When brackets or jacks so applied are opened, as shown in Figs. 1 and 85 2, a plank is laid thereon and serves as a support for the workmen. Additional layers or courses of shingles can then be applied to the roof formation, the first and possibly the second additional layer or course being placed 90 over the upper ends of the brackets, as best shown in Fig. 1.

Each bracket or jack comprises a comparatively thin supporting member 12 formed of a narrow strip of sheet metal curved upon itself, as at 13, to form an eye, and provided between its ends at opposite edges thereof with upstanding lugs 14, which are formed by cutting into the supporting member from the edges thereof and bending the material 100

upwardly or at right angles to the face of said member; these lugs being provided with transversely alined holes 15.

Near the other end of the supporting member along one edge thereof, spaced obliquely-disposed notches 16 are formed; these notches terminating in laterally-offset rounded extensions 17 into which the nails 11 are adapted to be entered, or said nails may be driven through the notches at said offset extensions; thus holding the supporting member in place on the roof.

Pivottally connected to the eye 13 of the supporting member is the lift or jack member 18. This member is also constructed of sheet metal bent into channel formation to provide opposite flanges 19, and through the lower or inner ends of these flanges, pivot openings 20 are formed. These pivot openings are in registration with the opening through the eye 13 of the supporting member, and a pivot pin 21 is passed through said eye and said openings 20, thus pivottally connecting the lift or jack member 18 with the lower end of the supporting member 12.

A series of connector or brace-supporting pins 22 are arranged in the channel-shaped lift or jack member, and they are spaced apart near the upper or outer end of said member and have opposite ends thereof fastened to the opposite flanges 19 of said lift or jack member.

23 designates a brace member by means of which the lift or jack member is maintained in desired angular relation to the supporting member 12. This brace member is also constructed of sheet material, preferably of heavier gage than the supporting member 12 and the lift or jack member 18 so that it will support a plank or similar object. The lift or jack member 18 is preferably of somewhat heavier sheet-metal gage than said supporting member.

One end of the brace member is curved upon itself to form an eye 24 and the other end is bent upon itself to form a hook 25. The eye 24 of the brace member 23 is positioned between the lugs 14 on the supporting member 12, and the opening through said eye is in registration with the holes 15 in said lugs; and through these openings is passed a pivot pin 26 serving to pivottally connect the inner or upper end of said brace member with said supporting member.

With a view of utilizing comparatively little space when not in use, and for convenience in transporting the brackets or jacks, they may be folded as shown in Figs. 3 and 4; the brace member 23 being swung downwardly or inwardly against the supporting member 12, after which the lift or jack member 18 may also be swung downwardly or inwardly against said supporting member, completely concealing the brace member. When in this position the device

can be easily applied to a roof, it simply being necessary to provide the nails 11, one for each of the notches 16, and hook the supporting member onto said nails, as best shown in Fig. 3. The lift or supporting member 70 may then be swung on its pivot 21, and while holding the same in angular relation to the supporting member, the brace member 23 may be swung on its pivot to engage the desired pin 22 of the lift or brace member, the pin selected being preferably the one that will dispose the brace member in a horizontal position, or approximately so.

The free end of the hook 25, as clearly shown in Fig. 2, will be positioned between the flat outer wall 27 of the lift or jack member 18 and one of the connector pins 22, and thus make it necessary to exert pressure manually in a vertical direction while gradually swinging the lift or jack member inwardly or toward the supporting member. When a plank is laid upon the brace members of two spaced brackets or jacks, the tendency of the hook ends of the brace members is to more securely lock themselves to the lift or jack members, and this tendency is increased under the weight of workmen moving about on the plank supported by said brace members.

Having thus described my invention, what I claim is:

1. A roof bracket, comprising a supporting member, a jack member pivottally connected to said supporting member, a brace member pivottally connected to said supporting member, and means for detachably connecting said brace member to said jack member at different points along the length of the same, said jack and brace members being foldable one over the other on and parallel with said supporting member.

2. A roof bracket, comprising a supporting member, a jack member pivottally connected to said supporting member, a brace member pivottally connected to said supporting member, and means for detachably connecting said brace member to said jack member at different points along the length of the same, said jack and brace members being foldable on said supporting member and said jack member concealing said brace member when both are in folded position.

3. A roof bracket, comprising a comparatively narrow thin supporting member adapted to lie against an inclined surface and having means for attachment to said inclined surface, said supporting member being provided at one end with an eye and between its ends with a pair of spaced lugs, a jack member pivottally connected at one end to the eye of said supporting member, and a brace member having one end disposed between said lugs and pivottally connected thereto, said brace member having its other end detachably connectable to said jack mem- 130

ber at different points along the length of the same and being foldable onto said supporting member and said jack member being foldable onto said brace member.

5 4. A roof bracket comprising a supporting member formed of narrow sheet material curved upon itself at one end to form an eye, a jack member also formed of sheet material bent into channel formation in cross 10 section and having the flanges thereof lying against opposite ends of said eye, a pivot pin passed through said eye and the flanges of said jack member to pivotally connect the latter with said supporting member, a series 15 of pins spanning the space between the flanges of said jack member along a portion of its length, and a brace member pivotally connected to said supporting member between its ends and having a hook at its outer end adapt- 20 ed for selective attachment to the pins of said jack member.

5. A roof bracket, comprising a supporting member having an eye at one end, means of attachment near its other end and a pair of spaced lugs between said ends, a brace member having one end disposed between said lugs and pivotally connected thereto and having a hook at its other end, and a jack member of channel formation having its flanges lying against opposite ends of the eye of said supporting member and being pivotally connected thereto, said channel member having connector pins spanning the flanges of said jack member and spaced from the outer wall thereof, the hook of said brace member being adapted to engage any of said connector pins and be positioned with its outer end between the selected connector pin and the outer wall of said jack member.

In testimony whereof, I affix my signature.

LOUIS P. REIMANN.
